ATTORNEY.

UNITED STATES PATENT OFFICE.

FRIEDRICH OTTO HEINIG, OF PHILADELPHIA, PENNSYLVANIA.

DESIGN FOR TRIMMING.

SPECIFICATION forming part of Design No. 21,743, dated August 2, 1892.

Application filed May 28, 1892. Serial No. 434,800. Term of patent 3½ years.

To all whom it may concern:

Be it known that I, FRIEDRICH OTTO HEINIG, a citizen of the United States, residing in the city and county of Philadelphia, State of Pennsylvania, have invented and produced a new and original Design for Trimming, of which the following is a specification, reference being had to the accompanying drawing, forming part thereof.

The leading feature of my design for a trimming is a double cord, the two lengths thereof extending partly parallel in zigzag direction, the angles of one cord extending above the top edge of the head and those of the other cord extending below the lower edge thereof, the top and bottom angles of said cords alternating with serpentine loops on said edge.

In the drawing, A designates a head, and B serpentine loops on the opposite edges thereof. C designates a cord, which extends in serpentine direction on the face of said head and has its bends or angles extending beyond the edges thereof and projecting alternately between the loops B. The cord C is double and parts of the two lengths thereof extend parallel. The angles of one cord are above the top edge of the head and those of the other cord are below the bottom edge thereof. 20 25

I claim—

The design for trimming, substantially as shown and described.

FRIEDRICH OTTO HEINIG.
